CLAIM

I claim the ornamental design for an electronic device, as shown and described.

DESCRIPTION

FIG. 1 is a perspective view of the electronic device, showing my new design;

FIG. 2 is a front side view thereof;

FIG. 3 is a rear side view thereof;

FIG. 4 is a left side view thereof;

FIG. 5 is a right side view thereof;

FIG. 6 is a top side plan view thereof; and,

FIG. 7 is a bottom side plan view thereof.

The broken lines illustrate portions of the electronic device that form no part of the claimed design.
